CLAIM

The ornamental design for eyeglasses, as shown and described.

DESCRIPTION

FIG. 1 is a front perspective view of the eyeglasses showing my new design;

FIG. 2 is a front elevational view thereof showing only a part of the side straps for ease of illustration;

FIG. 3 is a top plan view thereof showing only a part of the side straps for ease of illustration;

FIG. 4 is a left side elevational view thereof with the side straps in the open position;

FIG. 5 is a partial view of the left side thereof when viewed from inside the looped headband looking outwardly, showing only a part of the frame for ease of illustration;

FIG. 6 is a rear perspective view thereof;

FIG. 7 is a rear elevational view thereof, showing only a part of the side straps for ease of illustration;

FIG. 8 is a right side elevational view thereof with the side straps in the open position; and,

FIG. 9 is a partial view of the right side thereof when viewed from inside the looped headband looking outwardly, showing only a part of the frame for ease of illustration.
